UNITED STATES PATENT OFFICE.

CHARLES WAGNER, OF GRANTWOOD, NEW JERSEY, AND AUGUST HORMEL, OF NEW YORK, N. Y.

PAPER-CURING MACHINE.

1,167,730.

Specification of Letters Patent. Patented Jan. 11, 1916.

Application filed June 24, 1915. Serial No. 38,050.

To all whom it may concern:

Be it known that we, CHARLES WAGNER, a citizen of the United States, residing at Grantwood, county of Bergen, and State of New Jersey, and AUGUST HORMEL, a citizen of the United States, residing at New York city, county and State of New York, have invented certain new and useful Improvements in Paper-Curing Machines, of which 10 the following is a specification.

This invention relates to a novel machine for curing paper, and more particularly for curing such paper as is subsequently used for multicolor lithographic printing. As is 15 well known, all paper either shrinks or expands owing to changes in the temperature, etc., so that the consecutively imprinted patterns or designs of different colors will not register unless the paper has exactly the 20 same temperature as the press room of the printing establishment. Our improved machine is designed to be installed within the press room and the air of this room is for a certain length of time blown against the 25 paper to be subsequently printed. For this purpose a bipartite housing of novel construction is provided into a chamber of which a plurality of sheets of paper are introduced to be there subjected to the action 30 of a number of blowers.

The invention also comprises other novel features of construction more fully pointed out in the appended specification and claims.

In the accompanying drawing, Figure 1 35 is an end view of a paper curing machine embodying our invention; Fig. 2 a longitudinal vertical section thereof; Fig. 3 a plan view of Fig. 1; Fig. 4 a vertical cross section on line 4—4, Fig. 3; Fig. 5 a horizontal cross section on line 5—5, Fig. 1; Fig. 40 6 an end view partly in section of a machine showing modified paper-suspending means; and Fig. 7 a side elevation of the automatic paper-delivery device.

Our improved paper curing machine 45 comprises essentially a pair of opposed spaced housings 10 forming a paper curing chamber 11 therebetween. Each housing 10 is composed of a pair of upright end frames 50 12 closed at their inner sides by metal sheets 13. Frames 12 are rabbeted as at 14 for the reception of the outer edges of metal sheets 15 that extend substantially along the top, the outer edge and the bottom of said 55 frames. The opposed inner edges of the

sheets 15 are secured to the flanges 16 of a middle frame 17. The inner vertical edges of the frames 12 of each housing are connected by an open-meshed wire netting 18 constituting an inner wall. The opposed 60 end frames 12 of the two housings thus formed are connected with each other by means of cross bars 19 while the middle of frames 17 is connected by a cross bar 20. For supporting the paper to be cured, a pair 65 of longitudinal rails 21 is shown to be provided, according to the construction illustrated in Figs. 1 to 5, said rails extending considerably beyond the housings as at 21^a and 21^b. Each of these rails is firmly at- 70 tached to a bracket 22 of the frame 12 of each housing near the top thereof while at its middle, said rail is supported by the slotted head 22^a of a bracket 23 forming part of frame 17. An eye 24 provided at the bot- 75 tom of this frame is engaged by a post 25 the upper end of which is fitted into an eye 26 of bracket 23 to which last named eye the bolt is clamped by a nut 27. To increase the stability of the housings, the end frames 80 thereof are connected by stay bars 28 that also pass through corresponding perforations of the middle frames 17.

Along the rails or track 21 is adapted to travel a truck 29 from which the paper 85 sheets 30 to be cured are suspended. Although we have shown but one truck in the drawings we desire it to be distinctly understood that we employ in practice two of such trucks, one for supporting the paper 90 while being cured, while the other truck is shifted upon either of the protruding track portions 21^a and 21^b for removing the previously cured paper from said truck and then charging it with fresh paper. 95

Each truck 29 comprises a pair of transverse axles 31 upon the ends of which flanged wheels 32 are loosely mounted that engage rails 21. The axles 31 are firmly connected by means of a pair of longitudinal braces 33 secured to said axles by clamps 34. Upon the axles 31 are adjustably mounted the sleeves 35 of a pair of longitudinal bars 36 of a length that is slightly less than the length of housings 10. Each 100 bar 36 is shown to be provided with a notched lower rib 37, each notch 38 being adapted for the reception of one or more sheets 30 of the paper to be cured whereby the paper is held in position by upwardly 110

movable eccentric clamps or dogs 39. After a truck 29 has thus been charged it is moved into a position between the two housings 10 to be here subjected to a heavy draft. For producing the latter there is mounted in each housing a pair of rotatable blowers 40 that throw the press room air from both sides against the suspended paper sheets and thereby cause the latter to assume the press room temperature in comparatively short time. Each of these blowers is shown to comprise a longitudinal shaft 41 mounted in corresponding bearings 42 of the end frames 12. Within housing 10 there is mounted upon shaft 41 in proximity to each end frame as well as at its middle, the hub 42 of a disk 43 provided with substantially radial flanges or ribs 44. To the latter are secured by means of screws 45 or otherwise, sheet metal vanes 46 the inner edges of which abut against the shaft 41 while their outer ends are slightly curved as clearly illustrated in Fig. 4. All of the blowers 40 receive simultaneous rotation from a main driving belt 47 engaging a pulley 48 mounted on the lower right hand blower shaft 41 (Fig. 1). A belt 49 transmits rotary motion from the shaft 41 to the superposed shaft 41^a which is in turn by means of a suitable belt transmission 50 connected to the upper shaft 41^b of the opposite housing 10, said shaft being connected to the blower shaft 41^c by belt 51. It will be seen that by the construction described all of the blowers 40 are simultaneously actuated to throw the air from opposite sides against and between the paper sheets suspended therebetween, thus effecting a quick, reliable and uniform curing of the same.

In lieu of suspending the paper to be cured from reciprocative trucks 29, a pair of continuously advancing endless carriers 52 supported by sprocket wheels 53 may be employed as illustrated in Figs. 6 and 7. Each of these carriers comprises a plurality of links 54 which links are supported along the lower carrier run by flanged guides or tracks 55, the sprocket wheels 53 and guides 55 being laterally adjustable so as to adapt the machine to paper sheets of different width. Each link 54 is provided with a clamp 56 into which one or more paper sheets 30 are manually or otherwise inserted, the finger 57 of each clamp being automatically opened at the end of the lower carrier run by an arm 58 so as to release the cured paper, the freed sheets being received by a suitable truck T.

For operating the carriers 52 a horizontal power shaft 59 is provided that transmits its motion through a speed-reducing worm gear 60 to a vertical shaft 61. The latter drives in turn a horizontal shaft 62 by

means of a speed-reducing worm gear 63 that may be coupled to said last named shaft by a hand lever 64. The shaft 62 finally drives one of the shafts 65, supporting the sprocket wheels 53 by means of stepped pulleys 66 and a belt 67. It will be seen that by the construction described, the paper sheets 30 upon being manually or otherwise attached to the carriers near the beginning of their lower run, travel slowly through the paper curing chamber to be automatically released at the end of such lower run after having assumed a temperature equal to that of the press room.

We claim:

1. A paper curing machine comprising a pair of opposed inwardly opening spaced housings to form a paper curing chamber therebetween, paper suspending means adapted to be introduced into said chamber, and blowers located within the housings and adapted to throw the air against the suspended paper.

2. A paper curing machine comprising a pair of opposed inwardly opening spaced housings to form a paper curing chamber therebetween, paper suspending means adapted to be introduced into and to be subsequently withdrawn from said chamber, and blowers located within the housings and adapted to throw the air against the suspended paper.

3. A paper curing machine comprising a pair of opposed inwardly opening spaced housings to form a paper curing chamber therebetween, a track extending through said chamber, movable paper suspending means supported by said track, and blowers located within the housings and adapted to throw the air against the suspended paper.

4. A paper curing machine comprising a pair of opposed inwardly opening spaced housings to form a paper curing chamber therebetween, each of said housings comprising a pair of end frames and a middle frame, and metal sheets extending along the top, outer side and bottom of such end and middle frames, a track extending along the inner side of each housing, paper suspending means supported by said track, and blowers located within the housings.

5. A paper curing machine comprising a pair of opposed inwardly opening spaced housings to form a paper curing chamber therebetween, each of said housings comprising a pair of end frames and a middle frame, and metal sheets extending along the top, outer side and bottom of such end and middle frames, a track extending along the inner side of each housing, paper suspending means supported by said track, blowers located within the housings, and common means for rotating said blowers.

6. A paper curing machine comprising a pair of opposed inwardly opening spaced

5 housings to form a paper curing chamber therebetween, a track extending through said chamber near the top thereof, paper suspending means supported by said track and a pair of blowers located within each housing.

- 10 7. In a paper curing machine, a pair of spaced housings, to form a paper curing chamber therebetween each of said housings being composed of two end frames and a middle frame, metal sheets extending along the top, outer side and bottom of said end and middle frames, a paper supporting track extending through said chamber, a 15 pair of superposed horizontal shafts mounted within the end frames and extending through the housing, blower vanes on said shafts, and means for simultaneously rotating said shafts.
- 20 8. In a paper curing machine a pair of spaced housings, to form a paper curing chamber therebetween, each of said housings being composed of two end frames and a

middle frame, metal sheets extending along the top, outer side and bottom of said end 25 and middle frames, a paper supporting track extending through said chamber, a pair of superposed horizontal shafts mounted within the end frames and extending through the housing, disks secured to said 30 shafts in proximity to the end frames, curved vanes carried by said disks, and means for simultaneously rotating said shafts.

9. A paper curing machine comprising a 35 pair of opposed spaced housings, to form a paper curing chamber therebetween, open meshed walls at the inner sides of said housings, paper-suspending means within the curing chamber, and blowers located within 40 the housings and adapted to throw air through the open meshed walls into said chamber.

CHARLES WAGNER.
AUGUST HORMEL.
